GARMENT CARRIER

Israel Dukes, Philadelphia, Pa.

Application May 9, 1934, Serial No. 724,680

10 Claims. (Cl. 206—7)

The invention relates to a garment carrier of the type in which a hanger for garments of different kinds is removably secured within a garment box designed particularly for utilization therewith, or a box of standard construction, and involves an improvement in the garment hanger as well as the combination and arrangement of the hanger with respect to the box.

One of the principal objects of the invention is the provision of a garment carrier which is so constructed and arranged as to preserve the shape of the garments placed therein and minimize the wrinkling of the garments irrespective of the position in which the carrier itself may be placed. A further object of the invention is the provision of an improved garment hanger so constructed that it may be easily and quickly secured in position in the garment box and removed therefrom without damage to the hanger or to the box. A still further object of the invention is the provision of an improved garment hanger so constructed that it may be readily secured in position in the box after the garments have been positioned thereon, or the garments may be positioned upon the hanger after the hanger is secured within the box. A still further object of the invention is the provision of a garment hanger for supporting various articles of wearing apparel within a garment box and positioning the same therein in such a manner as to prevent any substantial movement thereof during the use of the carrier and irrespective of the position in which the carrier may be placed when in use. It is a still further object of the invention to provide a garment hanger having garment supporting means and garment positioning means thereon, both the garment supporting means and the positioning means being so constructed that they may be readily manipulated in securing them to the garment box and removing them therefrom, and to enable the garments to be easily placed thereon when the hanger is secured in position in the box. It is also an object of the invention to provide an improved garment hanger so constructed that it may be easily and quickly secured in position in a garment box designed especially for use therewith, or in a box of standard construction.

Still other objects and advantages of the invention will be apparent from the following description taken with the accompanying drawings, wherein:

Fig. 1 is a perspective view showing the improved garment hanger in position in a box de-

signed particularly for use therewith, with the latter in open position;

Fig. 2 is a fragmentary plan view of the bottom portion of the box illustrated in Fig. 1, showing the manner in which the garment hanger is secured in position therein and removed therefrom; 5

Fig. 3 is a detailed sectional view showing the garment hanger in position in the box, and illustrating by dotted lines the manner in which the hanger is manipulated when in position in 10 the box;

Fig. 4 is a transverse sectional view through the box and hanger showing the approximate position of the hanger and positioning means when the carrier is in upright position; 15

Fig. 5 is a fragmentary perspective view showing the manner in which the improved hanger may be utilized with a garment box of standard construction;

Fig. 6 is a fragmentary sectional view of the 20 carrier illustrated in Fig. 5, showing the lid portion of the box in place and the approximate position of the hanger with respect to the box when the carrier is in horizontal position;

Fig. 7 is a fragmentary perspective view of 25 a slightly modified form of hanger; and

Fig. 8 is a sectional view of the modified form of hanger taken on the line 8—8 of Fig. 7.

Although the novel form of garment hanger disclosed herein has been designed primarily 30 for utilization with a collapsible form of garment box such as illustrated in Figs. 1 to 4 of the drawings, in which case the hanger is so designed as to be removably secured beneath an end flap of the bottom portion of the box, the construction of the improved hanger is such that it may also be employed with a standard form of garment box by the engagement of the hanger support about the end wall of such a box as disclosed in Figs. 5 and 6 of the drawings. 40

As shown in Figs. 1 to 4, my novel form of garment hanger is employed with an improved form of garment box of collapsible type comprising a bottom portion 10 and a top portion or closure 11. The bottom portion 10 is provided 45 with a bottom wall 12 and with oppositely arranged side walls 13 and 14, and an extension on the bottom wall 12 forms the end wall 15 which is provided with a flap portion 16 which folds over into the interior of the bottom portion 50 into engagement with the flaps 17 and 18 integral with the ends of the side walls 13 and 14 respectively. The end wall 15 and the flap 16 thereon are preferably secured together by staples or wire stitching 19 extending through 55

the flaps 17 and 18 on the side walls, and similar stitching is preferably employed near the center of the end wall, midway of the upper and lower edges thereof, as shown at 20.

5 The top portion 11 of the box is provided with a top wall 21, oppositely arranged side walls 22 and 23, and an end wall 24 having an interior flap portion 25 thereon secured in position by means of staples or wire stitches 26 extending therethrough and engaging with end flaps integral with the side walls 22 and 23 as heretofore described with respect to end flaps 17 and 18. An end wall 27 in common with the top and bottom portions of the box is preferably integral with the bottom wall 12 and the top wall 21 and is scored along the parallel lines 28 and 29 coinciding with the meeting edges of this common end wall and the top and bottom walls 12 and 21. The cut-away portions 30 and 31 between adjacent ends of the side walls of the top and bottom portions of the box and the lines of scoring 28 and 29 facilitate the hinging of the top portion of the box to the bottom portion in a manner well known in the art.

15 25 My improved form of hanger is removably secured in position in the garment box by means of an elongated support 34 folded along a longitudinal line so as to provide two overlapping portions 35 and 36 designed to be removably inserted between the end wall 15 and the interior flap 16, with the opposite ends thereof positioned beneath the end flaps 17 and 18. Preferably the ends of the support 34 are beveled as shown at 37 in order to facilitate the insertion 30 of the support into the pocket provided by the end wall 15 and the flap 16, and the folded edge thereof is provided with a cut-away portion 38 for engagement about the fastening means 20.

As disclosed herein, a garment positioning frame 39 of such a size as to fit within the bottom portion 10 of the box is attached to the elongated support 34 by means of a pair of spaced hinging members 40 and 41. The hinging members 40 and 41 are preferably scored 45 transversely thereof along two parallel lines 42 and 43, the former coinciding with the lower lateral edge of the support, and the latter being substantially midway of the lateral edges thereof.

A garment supporting member 44 designed 50 particularly for holding a coat or similar piece of wearing apparel is provided with a central hinging member 45 located between the hinging members 40 and 41 for the garment positioning frame. The hinging member 45 is likewise secured to the support 34 along a scored line 46 substantially midway of the longitudinal edges of the support, and is scored along a line 47 substantially coinciding with the lower longitudinal edge of the support.

60 As I have disclosed the same herein, the support 34, the positioning frame 39, and the garment supporting member 44 are preferably formed from a single piece of suitable material, such as cardboard, pasteboard, fiber-board, etc. 65 The hinging member 45 is preferably separated from the hinging members 40 and 41 as shown at 48 in order to provide ample space for the upturned collar of a coat or other garment positioned on the garment supporting member 44, and the portions 49 are preferably folded over 70 upon the body of the garment supporting member and secured thereto by staples or wire stitching 50 in order to provide a suitable support for the shoulders of the garment. The central portion 51 of the supporting member 44 may be cut

along the line 52 and folded downwardly and stitched to the body of the supporting member 44 as shown at 53 to provide a support for trousers or other similar garments.

The opposite side edges of the garment positioning frame 39 are cut away as shown at 54 for receiving trousers or other articles of apparel folded about the positioning frame in well known manner, and the lower edge of the positioning frame is preferably folded over upon itself and 10 stitched or stapled thereto as shown at 55 in order to form a reinforcement for the edge.

As illustrated in Fig. 2 of the drawings, the hanger is secured in position in the bottom portion 10 of the box by collapsing the end wall 15 15 of the box either partially or completely and inserting the hanger support 34 between the interior flap 16 and the end wall, with the ends of the support between the end wall proper and the inwardly turned flaps 17 and 18 on the side walls, 20 the cut-away portion 38 engaging about the central fastening means 20. The end wall of the bottom portion of the box is then raised into its upright position whereupon the support for the hanger is firmly and securely held in position 25 against removal until the end wall is again moved into its collapsed position. With this improved form of hanger, the garments may be positioned thereon before the hanger is secured within the box, or they may be positioned on the hanger 30 after it is secured within the box. By securing the hinging portions 40 and 41 of the positioning frame to the support 34 along a scored line midway of the longitudinal edges of the support, and by scoring these hinging portions along a line 35 parallel thereto and substantially coinciding with the lower edge of the support, a hinged connection is provided by means of which the garment positioning frame 39 may be readily folded into the dotted line position 56 shown in Fig. 3 to permit a coat or similar piece of wearing apparel to be easily placed upon the garment supporting member 44, whereupon trousers or other articles of apparel may be placed in the box transversely thereof and the positioning frame folded into position 45 thereover and portions of the trousers or other apparel then folded over the top of the positioning frame.

The provision of the spaced lines of scoring in the hinging members 40 and 41 provides a hinging connection whereby the garment positioning frame 39 may be folded into a position outside the box and clear of the garment supporting member 44, in which position it will remain and not interfere with the placing of garments on 55 the supporting member 44 when the hanger is in the box and the latter is in a horizontal position. The spaced lines of scoring transversely of the hinging member 45 likewise provide a hinging connection permitting the garment supporting 60 member 44 to be folded into a stable position outside of the box where it will not interfere with the positioning of garments upon the positioning frame 39 in case it is desired to use the hanger in a manner different from that heretofore described. The hinging connections herein disclosed also provide means for attaching the frame 39 and the supporting member 44 to the support 34 in such a manner as to permit the various parts of the hanger to position themselves in 65 the box when in either a horizontal or an upright position.

As heretofore referred to, my improved form of garment hanger is designed to be employed with a standard form of garment box in addition 70

to the particular type of box heretofore described, and I have disclosed in Figs. 5 and 6 the manner in which the hanger may be so used. In this case the opposing folded portions 35 and 36 of the support are engaged about the free edge 57 of one of the end walls 58 of the bottom portion of the garment box, and when the garments are in position upon the hanger the hanger support 34 is retained on the end wall of the bottom portion of the box by the engagement of the top 59 of the box therewith, as clearly shown in Fig. 6.

In the modified form of hanger shown in Fig. 7, the opposing folded portions 35 and 36 of the support are secured together by means of staples 15 or wire stitching 60 passed through the ends thereof. While this form of support may be utilized with a box of the type disclosed in Figs. 1 and 4, it will be understood that it is not designed to be used with a standard form of box of the type shown in Figs. 5 and 6.

I have shown my improved form of box provided with fastening means in the form of a strap 61 having one end thereof secured to the end wall of the top portion of the box and the opposite end provided with fastening means 62 for engagement with cooperating fastening means 63 on the bottom wall. If desired, the box may also be provided with a handle 64 preferably secured to the end wall of the top portion as illustrated in Figs. 1, 4 and 6.

While I have disclosed a preferred form of my invention, together with certain modifications thereof, it will be understood the various changes in form and arrangement of parts may be made without departing from the invention as it is described herein and illustrated in the accompanying drawings, and that such changes are contemplated as come within the scope of the appended claims.

Having thus described my invention, what I desire to secure by United States Letters Patent is:

1. A garment hanger comprising an elongated support adapted to be removably secured to the end wall of a garment box, a garment positioning frame adapted to fit within the garment box with the edges thereof adjacent the side walls of the box and having spaced hinging members connecting the same to said support, and a garment supporting member having a hinging member connecting the same to said support, said last mentioned hinging member being positioned between said spaced hinging members and in spaced relation thereto to receive a garment element therebetween.

2. A garment hanger comprising an elongated support adapted to be removably secured to the end wall of a garment box, a garment positioning frame adapted to fit within the garment box with the edges thereof adjacent the side walls of the box and having spaced hinging members connecting the same to said support, and a garment supporting member having a hinging member connecting the same to said support, said last mentioned hinging member being positioned between said spaced hinging members and in spaced relation thereto to receive a garment element therebetween, said spaced hinging members being scored transversely thereof along a pair of spaced, parallel lines to permit said members to be readily folded about said support.

3. A garment hanger comprising an elongated support adapted to be removably secured to the end wall of a garment box, a garment positioning frame adapted to fit within the garment box with

the edges thereof adjacent the side walls of the box and having spaced hinging members connecting the same to said support, and a garment supporting member having a hinging member connecting the same to said support, said last mentioned hinging member between said spaced hinging members and in spaced relation thereto to receive a garment element therebetween, the hinging member for said garment supporting member being scored transversely thereof along a pair of spaced, parallel lines to permit said garment supporting member to be readily folded about said support.

4. A garment hanger comprising a support adapted to be removably secured within a garment box, a garment supporting member, and a hinging member connecting said garment supporting member to said support and scored transversely thereof along two parallel lines, one in alignment with one longitudinal edge of said support and the other intermediate the longitudinal edges of said support.

5. A garment hanger comprising an elongated support folded upon itself along a line extending longitudinally thereof to provide opposing portions for receiving the free edge of a wall of a garment box, a garment supporting member having an attaching portion connecting the same to said support along a line intermediate the fold of said support and one of the longitudinal edges thereof, said attaching portion having a hinged connection to said support.

6. A garment hanger comprising an elongated support folded upon itself along a line extending longitudinally thereof to provide opposing portions for receiving the free edge of a wall of a garment box, a garment positioning frame having spaced hinging members connecting the same to said support along a line intermediate the fold of said support and one of the longitudinal edges thereof, and a garment supporting member having a hinging connection with said support between said spaced hinging members and along a line intermediate the fold of said support and said longitudinal edge.

7. A garment hanger comprising an elongated support, a garment positioning frame having spaced attaching members connecting the same to said support along a scored line intermediate the longitudinal edges of said support, and a garment supporting member having an attaching portion between and spaced from said attaching members for connecting the same to said support intermediate the longitudinal edges thereof, said attaching portion being scored transversely thereof in alignment with the longitudinal edge of said support.

8. The combination in a garment carrier of a box bottom portion, a top portion therefor, a support adapted to be removably secured within said box bottom portion, a garment positioning frame fitting within said box bottom portion and having spaced attaching members connecting the same to said support, and a garment supporting member fitting within said garment positioning frame and having an attaching portion between and spaced from said spaced attaching members and connecting the same to said support.

9. The combination in a garment carrier of a box bottom portion having an upstanding end wall, an elongated support folded upon itself along a line extending longitudinally thereof for engagement with the opposite faces of said end wall, a garment supporting member having a hinging member connecting the same to said support.

support, and a box top portion cooperating with said box bottom portion to retain said support in position upon said end wall.

10. In a garment carrier, the combination of
5 a box bottom portion having a bottom wall, side
walls, and an end wall, a box top portion having
a top wall, side walls and an end wall, said bot-
tom and top portions having one end wall in
common, a support removably secured to the
10 said end wall of said bottom portion, a garment
positioning frame fitting within said bottom por-

tion and having spaced attaching members con-
necting the same to said support, a garment sup-
porting member fitting within said garment po-
sitioning frame and having an attaching portion
between and spaced from said spaced attaching
members and connecting the same to said sup-
port, means for retaining said top portion in po-
sition on said bottom portion, and carrying
means on the said end wall of said bottom por-
tion.
